SHEAR PIN CUTOUT FOR STOKER MOTORS

Filed March 16, 1950

UNITED STATES PATENT OFFICE

2,628,337

SHEAR PIN CUTOUT FOR STOKER MOTORS

Delmond L. Getz, Springfield, Ohio, assignor to
 The Steel Products Engineering Company,
 Springfield, Ohio, a corporation of Ohio

Application March 16, 1950, Serial No. 149,953

3 Claims. (Cl. 318—475)

1

This invention relates to stoker systems and more particularly to a safety drive for the operation of the stoker.

In the ordinary stoker system such as that used for domestic and the small industrial installations, it is common to provide a drive motor for operating a blower and fuel feeding mechanism under the control of a thermostat or other regulating mechanism in order to maintain a desired temperature or pressure condition within an enclosed space. For safety purposes it is likewise the practice to utilize a shear pin in the drive unit for coupling the driving and driven members together, the pin having such size and shape, and corresponding strength that it will release or shear when a load in excess of a safe value is encountered. For instance, if a piece of iron or other solid object is present in the body of fuel, its entry into the fuel supply means may cause damage, and to prevent this from arising the shear pin construction is employed.

The rupture of the shear pin serves to prevent damage to the drive mechanism, but unless some additional provision is made, the drive motor would normally continue in operation. This would not only unnecessarily continue the operation of the motor without accomplishing any feeding of fuel, but it would continue the blower in operation and this would result in the burning down of the fuel remaining in the retort. In the absence of a fresh and continuing supply of fuel, the existing fuel bed would quickly become thin, and soon burn out entirely, with the development of excessive temperatures and possible damage to the retort or tuyères.

In accordance with the present invention, the shear pin is coupled with additional actuating mechanism which has a normal position in which the stoker system continues to operate in all respects under its usual controls such as temperature, pressure, or the like regulation. However in the event that the shear pin is broken, there is a resultant relative rotation between the driving member which continues to operate for a short interval, and the driven member coupled to the fuel supply means which no longer operates because of the rupture of the shear pin. As a result of this relative rotation between the driving and the driven members, the actuating device is shifted away from its normal position and this causes the operation of a control which is effective to stop the operation of the drive, and consequently of the blower. Thus within a short interval after the rupture of the shear pin, which interval is much less than that which could re-

2

sult in a dangerous or damaging burning out the fuel still in the retort, the drive is stopped and there is no further supply of either fuel or air, and the entire system is thus fully protected.

It is also a feature of the invention that in response to such operation, an indication or signal is afforded, either audible or visual, or both, so that the attendant or house occupant will know of the condition, and can take the necessary steps to clear the obstruction, and restore the system to operation.

It is therefore a principal object of the invention to provide a stoker control system in which there is provision for stopping the operation of the system upon the breakage of the shear pin thereby not only assuring against damage to the feeding structure, but preventing any damage to the retort, by reason of the burning out of the fuel bed thereon.

It is a further object to provide such a system incorporating a visual or audible indication of such breakage and the fact that the system is no longer in operation.

It is a still further object to provide such an arrangement which is simple in construction and which can be readily installed both on new equipment and likewise on existing equipment already in use.

Other objects and advantages will be apparent from the following description, the accompanying drawings and the appended claims.

In the drawings,

Fig. 1 is a side elevational view with parts broken away showing a typical stoker installation embodying a hopper and the fuel supply means for delivering the fuel to the retort;

Fig. 2 is a vertical sectional view on a larger scale showing the mechanism in accordance with the invention which is associated with the shear pin, the parts being in the normal driving relationship;

Fig. 3 is a view similar to Fig. 2 but showing the parts following the rupture of the shear pin;

Figs. 4 and 5 are vertical sectional views on the lines 4—4 and 5—5 respectively of Fig. 2; and

Fig. 6 is a diagrammatic view showing the circuit connections for use in the operation of the system.

Referring to the drawings which disclose a preferred embodiment of the invention, Fig. 1 shows a side view of a stoker installation in which there is a fuel receiving hopper 10 having a supply cover 11 through which it may be loaded with coal or other solid fuel. The drive motor is indicated at 12 having a V-belt drive 13 to a pulley

14 mounted on gear case 15. Various types of gear mechanism may be employed providing for the operation of the feed worm 16 at a suitably slow rate of speed. Preferably the mechanism is one which will advance the feed worm through intermittent steps of movement, and may embody a ratchet drive mechanism such as that described in copending application Serial No. 126,962, filed November 14, 1949, and assigned to the same assignee as this application. The feed worm extends through the lower part of the hopper 10, where it picks up the fuel and delivers the same into the retort 18 where the burning takes place.

Pulley 14 also provides for the operation of a blower or fan indicated at 20 which supplies air under suitable pressure through wind tunnel 21 and from it into the tuyères 22 in the retort.

Referring more particularly to Fig. 2, the outside wall of the gear case 15 is shown as receiving a ball bearing 30 which rotatably supports sleeve 31 to which is connected a driving gear 32 having ratchet teeth 33 thereon. Suitable mechanism is provided in the gear case 15 for the rotation of gear 32 in a series of step-by-step movements, under the control of the time and temperature or pressure mechanism, in order to accomplish the desired temperature regulation. The sleeve 31 has a portion 35 which extends outwardly of the gear casing, suitable packing 36 being employed to prevent escape of lubricant from the bearing 30. Rotatably mounted within the sleeve 31 is the driven member or shaft 40 which is directly connected to the feed worm 16, providing for the operation of the worm when the shaft is turned. The shaft 40 has an overhanging end portion 41 which is squared or of other non-circular shape by means of which it can be turned by hand in case of necessity.

In order to couple the driving member or sleeve 31 with the driven member or shaft 40, a shear pin 45 is provided which is of suitable length to extend through correspondingly aligned bores in both the sleeve and the shaft. Thus when so assembled, the shear pin acts as a connecting link and transmits the driving torque from the sleeve to the shaft. When however the feed worm encounters a heavy obstruction and further turning of the shaft 40 is prevented, the strength of the shear pin is such that it will then rupture before any damage occurs with respect to the mechanism itself. This effectively interrupts the drive for the fuel feed mechanism, but does not stop the drive motor and thus the blower 20 remains in operation, continuing to supply combustion air to the retort with consequent objectionable burning out of the fuel bed.

In order to prevent such objectionable condition an actuating member in the form of a sleeve 50 is mounted upon the overhanging end of drive sleeve 35, sleeve 50 having an intermediate outwardly extending flange 51 and oppositely aligned apertures 52 which receive the outwardly extending ends of shear pin 45, this relationship being clearly shown in Fig. 5. Also, one side of each end of the shear pin is provided with a flat indicated at 53 and this flat is adapted to be received beneath the overhanging flange 51 of the actuating member so that when the parts are in the position shown in Fig. 2, the shear pin is positively locked in position and cannot drop out as it revolves even though there may be no frictional force between the driving and the driven members.

This is the normal position of the actuating member 50, and in order to retain it in that

position, a biasing means is provided comprising a compression spring 55 which abuts against a collar 56 secured by means of set screw 57 to the squared end 41 of shaft 40. Normally, therefore, the actuating member 50 occupies the position shown in Fig. 2 in which the pin 45 is prevented from falling out of its driving position.

It is desired to provide for movement of the actuating member 50 axially of the sleeve 35 in response to the rupture of the shear pin. For this purpose the inner face of the disk portion 60 of the sleeve 50 is provided with cam surfaces 61 in the form of a flat V, on opposite sides of the shaft 40. A pin 62 is fixed in shaft 40 and lies normally at the bottoms of the V-shaped groove formed by these cam surfaces. This allows the actuating member 50 to move to its normal righthand position as shown in Fig. 2 for continuing operation of the stoker.

In response to the rupture of the shear pin, the outer ends of the pin break off from the inner part which remains in shaft 40, and while shaft 40 immediately stops, the drive member or sleeve 31 continues to be driven by the drive motor. Since the outwardly projecting end of the shear pin 45 remains in interfitting relation in slot 52, it is evident that the drive between sleeve 35 and the actuating member 50 will continue. Thus the sleeve rotates, in progressive increments or steps in the type of drive mechanism referred to above, and as this rotation continues, the pin 62 fixed in the shaft is now forced up along the cam surfaces 61 of disk 60. As this relative rotation progresses, therefore, the disk 60 and the actuating member 50 will be cammed away from the sleeve, or toward the left as shown in Figs. 2 and 3, thereby shifting the position of the actuating member and causing it to pull away from the broken ends of the shear pin, or to such a point that the shouldered portions 53 are no longer locked beneath the flange of the member 51. This allows for access to and withdrawal of the broken ends of the shear pin, or the same may fall out by gravity if they are downwardly positioned.

A control switch indicated at 70 is mounted in suitable location adjacent flange 51 and arm 71 pivotally connected with the switch is engaged by such flange 51. The circuits of the control switch 70 are indicated in the diagram in Fig. 6. The normal circuit is completed through switch arm 72 which supplies an energizing voltage to the operating solenoid of a relay which closes the main motor circuit at 74, under the control of various timers, thermostats, pressure, safety and such other control mechanism as is normally provided, all such control devices being indicated diagrammatically and marked T. It will be understood that in the normal operating condition with the actuating member 50 in its righthand position as shown in Fig. 2, switch 72 remains closed and the system operates in all respects in a normal manner.

The switch 70 has another contact arm 75 and this contact is normally open but closes when the parts occupy the alternate position as indicated in Fig. 3. Not only does this movement result in opening switch 72, causing the stoppage of the motor and of the driving operations as well as stopping the operation of the blower, but it also completes a circuit to indicating mechanism diagrammatically illustrated as a visual indicator 76 and an audible indicator 77, either or both of which may be employed. Thus upon the occurrence of the fracture of the pin, the drive is cut

off and an indicating signal energized so that the attendant may be advised and take the proper steps to restore the system to use.

In such restoring operation, after first clearing the obstruction from the feed worm, the actuating member 50 is preferably rotated to bring its slot 52 into alignment with the remaining portion of the shear pin within the shaft 48, and the remaining piece of the broken pin removed and a new pin inserted. The actuating member 50 is manually held against the spring 55 during this operation, and when released, it will move into the interlocking position shown in Fig. 2 under the spring action. This restores the system to its original position of operation, and at the same time results in the cutting off of the warning signals and the reenergization of the relay 73, thereby placing the operation of the system fully under the other controls T, for continued operation in the usual way.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a stoker system for supplying fuel and combustion air to a retort, the combination of a driving member in the form of a sleeve, a driven member in the form of a shaft within said sleeve, a shear pin extending through said sleeve and said shaft and normally coupling said driving and said driven members together, an actuating member loosely mounted on said sleeve and having parts drivingly engaged by said shear pin to normally cause rotation of said actuating member with said driving and driven members, means on said actuating member overlying and retaining said shear pin in assembled position, means for yieldably biasing said actuating member toward a normal position overlying said shear pin, means positively operable upon relative rotation between said driving member and said driven member for moving said actuating member on said sleeve following the shearing of said pin, and control means engaged by said actuating member upon movement thereof to terminate the operation of said system.

2. In a stoker system for supplying fuel and combustion air to a retort, the combination of a driving member in the form of a sleeve, a driven member in the form of a shaft within said sleeve, a shear pin extending through said sleeve and said shaft and normally coupling said driving and said driven members together, an actuating member movably mounted on said sleeve and having parts overlying portions of and drivingly engaged by said shear pin, said shear pin having

a shoulder engaged beneath said actuating member in the normal position of the latter providing for locking said pin in operative position, a biasing spring urging said actuating member axially of said sleeve and normally maintaining said actuating member in said overlying position with respect to said pin, camming means operably carried by said actuating member and said driven member and operable upon the shearing of said pin and the resultant relative rotation of said driving member and said actuating member with respect to said driven member for camming said actuating member away from said normal position, and means operative in response to said movement away from said normal position for stopping the operation of said system.

3. In a stoker system for supplying fuel to a retort, the combination of a driving member in the form of a sleeve, a driven member in the form of a shaft within said sleeve, a shear pin extending through said sleeve and said shaft and normally coupling said driving and said driven members together said pin having a part extending outwardly beyond said sleeve, an actuating member movably mounted on said sleeve and having parts drivingly engaged by said outwardly extending part of said shear pin, said shear pin having a shoulder engaged beneath said actuating member in the normal position of the latter providing for locking said retaining pin in operative position, a biasing spring normally maintaining said actuating member in said overlying position with respect to said pin, camming means operably carried by said actuating member and said driven member and operable upon the shearing of said pin and the resultant relative rotation of said driving member and said actuating member with respect to said driven member for camming said actuating member away from said normal position, and means operative in response to said movement away from said normal position for stopping the operation of said driving member.
